APPLIANCE FOR HEATING WATER FOR DOMESTIC USE

Filed Sept. 15, 1933

FIG. 1.

Maurice C. Oliphant Inventor

Ogle R. Singleton

Attorney

UNITED STATES PATENT OFFICE

2,007,872

APPLIANCE FOR HEATING WATER FOR
DOMESTIC USE

Maurice Englebert Oliphant, Crestline, Ohio

Application September 15, 1933, Serial No. 689,550

1 Claim. (Cl. 126—362)

My invention consists in a new and useful improvement in water heaters and is designed more particularly for use with a storage tank and gas or other suitable heater for domestic use. The particularly novel and useful feature of my invention is the provision of a heating chamber having a flexible copper diaphragm therein, and a system of piping whereby the unheated water is subjected to the effect of the heater by passage 5 through said diaphragm, and is circulated by the heating process for storage in a suitable tank.

While I have illustrated in the drawing filed herewith and have hereinafter fully described one specific embodiment of my invention, it is to be distinctly understood that I do not consider my invention limited to said specific embodiment, but refer for its scope to the claim appended hereto.

In the drawing:

Fig. 1 is a vertical section of my device.

Fig. 2 is a horizontal section on line 2—2 of Fig. 1.

My device, as illustrated in the drawing, has a tank 1 with the supply pipe 2 having its discharge end 3 near the bottom 4 of the tank 1. An outlet pipe 5 is provided at the bottom 4 of the tank 1, and is connected with the vertically disposed pipe 6 which is connected by the pipe 5' with the upper portion of the tank 1. Depending from the lower end of the pipe 6 there is a cast-iron jacket formed by the conical upper casting 7 and the conical lower casting 8 fastened together by bolts 9. Positioned between these castings 7 and 8 and extending across this chamber is the flexible copper diaphragm 10 which is held in position by the bolts 9 passed through it. This diaphragm 10 consists of the concavo-convex portion 11 and an annular flange 12 through which are ports 13. To the bottom of the lower casting 8 there is connected the drain pipe 14 with cock 15.

The convex portion 11 of the diaphragm 10 has an opening 16 disposed concentric with the pipe 6. Surrounding this opening 16, there is the copper pipe 17 integral with the concavo-convex portion 11 and extending upwardly within the pipe 6 to a point about mid-way of the length of the pipe 6 and considerably above the point of junction of the pipe 5 with the pipe 6. This pipe 17 has a diameter sufficiently small as to afford a space 18 between the outside of the pipe 17 and the inside of the pipe 6.

Any suitable form of heating means, as a gas burner 19, is provided below the lower casting 8, and a discharge pipe 20 is provided at the top 55 of the tank 1.

From the foregoing description of the details of construction of my improved device, its use and operation will be obvious. The water entering tank 1 through the supply pipe 2 will pass from the bottom 4 of tank 1 through pipes 5 and 6 to the center of the heating chamber and passing over the diaphragm 10 and through ports 13 will be heated in the lower portion 8 of the heating chamber by heat from the burner 19. The heated water will flow upwardly against the concavo-convex portion 11 of the flexible diaphragm 10 and through pipe 17 into pipe 6 and from pipe 6 through pipe 5' to the upper portion of the tank 1. As the heated water begins to flow from the pipe 17 into the pipe 6, suction in the pipe 6 will be thereby created which will cause a portion of the unheated water from pipe 5 to flow upwardly in the space 18 and join the heated water from the pipe 17, to flow into the upper portion of the tank 1. It will be obvious that the proportionate separation of the water discharged from pipe 5 into the pipe 6, a part going downwardly to the heating chamber and a part going upwardly to the tank 1, will depend upon the relative dimensions of the pipes 5, 6 and 17.

It is to be noted that since the diaphragm 10 is made of flexible copper and the unheated water is applied to its upper side and the heated water to its lower side, there will be a difference in expansion and that the diaphragm 10 will be constantly in vibration when the heating chamber is in operation, which will serve to prevent formation of lime deposit or scale upon the diaphragm 10. Under certain conditions of water, there is also galvanic action.

Having described my invention, what I claim is:

In a water heater, the combination of a heating chamber having an upper portion and a lower portion; a diaphragm separating said portions and provided with water ports adjacent the perimeter thereof; a storage tank; a discharge pipe from the bottom of said tank; a hot water supply pipe to the top of said tank; a third pipe connected at its bottom with the upper portion of the heating chamber and at its top with the supply pipe of the tank, and having the discharge pipe from the tank connected therewith intermediate its top and bottom and a fourth pipe communicating through said diaphragm and extending centrally therefrom, and within the third pipe in spaced relation to the inner walls thereof, to a point beyond the junction of the third pipe with the supply pipe from the tank.

MAURICE ENGLEBERT OLIPHANT. 55
